(57) **CLAIM**

The ornamental design for a trailer-hitch mounted seat, as shown and described.

DESCRIPTION

FIG. 1 is a perspective view of a first embodiment of a trailer-hitch mounted seat showing my new design in condition of use as attached to the broken line environment of a rear-mounted trailer hitch of a truck;

FIG. 2 is a perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a perspective view of a second embodiment of a trailer-hitch mounted seat showing my new design in condition of use as attached to the broken line environment of a rear-mounted trailer hitch of a truck;

FIG. 10 is a perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken line depiction of a truck in FIGS. 1 and 9 shows an environment of use, the broken lines forming no part of the claimed design. The broken lines upon the surface of the design, and areas within the broken lines, in all views depict portions of the trailer-hitch mounted seat that form no part of the claimed design.
